US0D1076328S

(12) United States Design Patent (10) Patent No.: US D1,076,328 S
(45) Date of Patent: * May 27, 2025

(54) ABSORBENT UNDERPANTS

(71) Applicant: DRYLOCK TECHNOLOGIES N.V.
Zele (BE)

(72) Inventor: Steven Smet, Zele (BE)

(73) Assignee: DRYLOCK TECHNOLOGIES N.V.
Zele (BE)

() Term: 15 Years

(21) Appl. No.: 29/823,400

(22) Filed: Jan. 17, 2022

Related U.S. Application Data

(62) Division of application No. 29/712,943, filed on Nov. 12, 2019, now Pat. No. Des. 979,181.

(30) Foreign Application Priority Data

May 10, 2019 (EM) 006433702-0001

CLAIM

The ornamental design for absorbent underpants as shown and described.

DESCRIPTION

FIG. 1 is a top, front, right side perspective view of absorbent underpants showing the new design, in a first embodiment thereof;

FIG. 2 is a top view thereof;

FIG. 3 is a bottom view thereof;

FIG. 4 is a left side view thereof, where the right side view is a mirror image;

FIG. 5 is a bottom view thereof, where the top side view is a mirror image;

FIG. 6 is a top, front, right side perspective view of absorbent underpants showing the new design, in a second embodiment thereof;

FIG. 7 is a top view thereof;

FIG. 8 is a bottom view thereof;

FIG. 9 is a left side view thereof, where the right side view is a mirror image; and,

FIG. 10 is a bottom view thereof, where the top side view is a mirror image.

1 Claim, 10 Drawing Sheets
